UNITED STATES PATENT OFFICE.

FRED F. BURDICK, OF MILTON, WISCONSIN.

COLLAPSIBLE CABINET.

1,141,036.

Specification of Letters Patent. Patented May 25, 1915.

Application filed June 20, 1914. Serial No. 846,334.

To all whom it may concern:

Be it known that I, FRED F. BURDICK, a citizen of the United States, and a resident of Milton, in the county of Rock and State of Wisconsin, have invented certain new and useful Improvements in Collapsible Cabinets, of which the following is a specification.

This invention relates to cabinets which are used for giving steam, light and other baths; and which are adapted for continuous or intermittent use; and which, when not in use can be collapsed, as it is termed, for storage or shipping.

The principal objects of the invention are to obtain a collapsible cabinet, provided with sheet metal panels and corners, which can be opened to an operative condition by a person manipulating but few of the parts thereof, without said person being required to move from a given position; and if open, can be closed in the same manner; to obtain a cabinet which is simple in construction, not liable to break or get out of order; and one which, when closed, can be stored or shipped without liability of breakage.

A further object is to obtain a cabinet of the kind named which operates, in the opening and closing thereof, in such manner as to be readily understood by a person not particularly skilled in mechanics.

Additional objects are set forth in this specification and in the claims.

I have illustrated a collapsible cabinet embodying this invention in the drawings accompanying and forming a part hereof, in which—

Figure 1 is a perspective of the device, in an operative condition. Fig. 2 is a perspective of said device in a closed condition. Fig. 3 is a side elevation of a modification of the device in a substantially closed condition. Fig. 4 is a side elevation of said modification with the parts thereof in a different position from that shown in Fig. 3; and Fig. 5 is a side elevation of said modification with said parts in a nearly opened condition.

The modification illustrated in Figs. 3, 4 and 5, consists in a construction which gives a shorter front than back, with a corresponding change to the sides, when the device is in an operative condition; while in the construction illustrated in Figs. 1 and 2 the front and back are substantially the same height.

A reference character applied to designate a given part indicates said part throughout the several figures of the drawing, wherever the same appears.

A is the front of the cabinet, and is illustrated as consisting of a sheet metal panel, attached at its side edges to corner pieces D. Front A is provided with an opening or doorway; and a is a door adapted to be opened, on hinges B, to admit a person to the cabinet, and to be closed to close said door way or opening. b is a latch to door a. The cabinet back is a sheet metal panel, attached to the rear corner posts D at its edges, in the same manner as is the front panel A, and is a substantial duplicate of said front panel, with the exception that there is no opening or door way thereto and no door thereon. The door a is provided with an aperture therethrough which is illustrated in Fig. 1, with a panel, say of glass, covering said aperture, and lettered C.

The sides of the cabinet, are substantially duplicates, but rights and lefts, and consist of parts e, e, which are hinged together by hinges f, and to the corner pieces D by hinges F.

G is the top of the cabinet, and consists of the part g which is rigidly secured to the rear corner pieces and to the back, and the part g¹ which is hinged to part g by hinges h, the hinged door g², and the movable slide G¹. Slide G¹ is provided with the aperture H, through which the head of the person using the cabinet may protrude.

The mechanism by means of which the opening of the cabinet from a closed position, or vice versa, is effected, comprises the several levers hereinafter described, which are attached to the corners D, the top G, and to each other, as follows: I, I¹ J are links, J¹ is a lever, and said links and lever are pivotally attached to corners D by pivots i, and j, respectively, and to each other by pivots i¹, and j¹.

K is a connecting tie rod, pivoted at its ends on pivots i¹ and j¹.

It is to be observed that lever J¹ is provided with a long member, of substantially the same length as are links I, I¹, and J, and with a short member, which is at substantially right angles to the long member. The top G and lever J¹ are connected by a two part link, having one of said parts, (m) attached to the end of said short member of lever J¹, by pivot N, and the other of its

parts (m^1) attached to top G by pivot n . Parts m , m^1 are connected together by pivot l .

The use of this cabinet, when set up, as in Fig. 1 of the drawings, is well known to the medical profession, and requires no description herein; nor is it necessary to describe the function or use of the electric conductors X, which are illustrated.

10 The modified construction which is illustrated in Figs. 3, 4 and 5, consists merely in shortening the front ones of the corners D, (lettered D¹ in said figures), and the corresponding cutting off of the tops of the side panels e, e. The result of this modification is that when the cabinet is in operative condition the top is inclined, instead of being in a horizontal plane, as is the case in the construction which is illustrated in Figs. 1
15 and 2.

The operation of the several mechanisms which form the essential embodiment of this invention is the same in all the constructions shown.

25 With the cabinet closed and lying down, as in Fig. 2, to put it in an operative condition, it is first stood on end, as in Fig. 3. The top G is then raised to straighten out the two part link m, m^1 . In Fig. 4 said top
30 is shown as partially raised, and with said link partially straightened; the parts m and m^1 being at an angle of more than ninety degrees to each other. The cover is to be continuously raised until the parts m, m^1 ,
35 are in a straight line. After said parts are in line said top G is lowered, being forced down, if required; thereby turning bell crank lever J^1 on its pivot j . Lever J^1 being tied to link J , (by pivot j^1) and to levers I,
40 I ^{1} , (by connection K), said links are also turned on their respective pivots, and the front and rear corners D are forced apart. Corners D moving apart, as above, draw panels e of sides E from the position where
45 they are shown in Figs. 2 and 3, (where they are in nearly parallel planes), through the position thereof which is illustrated in Fig. 5, into the position which is illustrated in Fig. 1. The cabinet can then be used as an ordinary cabinet of this kind.

To close the cabinet, that is to put it into condition for storage or shipment, the top G is raised until the front and rear corners D are brought adjacent to each other, with the panels *e* in nearly parallel planes, the joint of parts *m*, *m*¹, at pivot *l*, is broken and the top is lowered into the position which is illustrated in Figs. 2 and 3.

Y is a latch which locks the front and rear corners D together, by turning it on pivot y and engaging it with pivot y' , as in Fig. 2.

I claim:—

65 1. A collapsible cabinet comprising corner pieces, collapsible sides and a two part top, one of said parts attached to corresponding

corner pieces and the other part pivotally joined to said attached part, in combination with a plurality of series of links and levers which are respectively pivotally attached to the side faces of corner pieces and to each other, tie rods respectively connecting one of the series on a side to the other series on said side, and links respectively consisting of two parts which are pivotally joined together, and one of said parts pivotally connected to the pivoted part of said top and the other pivotally connected to one of the levers of said series; whereby when the members of said two-part links are in line and the pivoted member of said top is raised and lowered a corresponding movement of said collapsible sides is produced, and when said members of said two part links are not in line movement of said pivoted member of said top produces no movement of said collapsible sides.

2. A collapsible cabinet comprising corner pieces, a front wall provided with an opening therethrough, a door to said opening, collapsible sides respectively attached to said corner pieces, and a two-part top, one member of said top attached to corresponding corner pieces and the remaining member pivoted to said attached member, said pivoted member adapted to be turned into a plane parallel with the plane of said front wall when said cabinet is collapsed, in combination with a plurality of series of links and levers, the links and a lever and link, respectively, forming a series pivotally connected together and to corner pieces, tie rods connecting the series on a given side, links respectively consisting of members pivotally joined together, and means to pivotally attach one of said members to the lever of one of said series, and to pivotally attach the other member to the pivoted member of said top, whereby said pivoted member of said top may be turned on its pivots to move said collapsible sides when the members of said last named links are in line. 100 105 110

3. A collapsible cabinet comprising corner pieces, a top consisting of a member attached to corner pieces and a member pivoted to said attached member, sides respectively comprising panels which are joined together and to said corner pieces, all combined with a plurality of series of links, and a lever and link on both said sides, said series respectively comprising links which are pivoted to the side faces of said corner pieces, tie rods respectively pivotally connected to the series and respectively connecting the series on a side, and two part links consisting of pivotally connected members, means to pivotally connect one of said members to the pivoted member of said top and means to pivotally connect the other of said members to the lever of one of said 130

series, whereby the pivoted member of said top may be turned to turn the pivoted member connected thereto on the pivot connecting it to the pivoted member which is connected to said lever of said series, to bring said members of said two part links into and out of a substantially straight line, and when said members are in a substantially straight line said pivoted member of the top may be turned on its pivot to vary the relative position of the front and rear ones of said corner pieces.

4. A collapsible cabinet comprising corner pieces, a top consisting of a member attached to corner pieces and a member pivotally connected to said attached member, both said members provided with an opening thereto, a cover adapted to cover said openings, sides respectively consisting of panels which are pivotally connected and are also pivotally connected to corner pieces, a front provided with an opening and a door to close said opening in said front, in combination with a series consisting of a lever and a link and a series of links, the links and the lever and link of a series being pivotally connected, and pivotally connected to said corner pieces, tie

rods respectively connecting the series on a side of said cabinet, two part members, 30 and means to pivotally connect one member of said two part member to the pivoted member of said top and to pivotally connect the other member to a lever of one of said series, said two part members adapted to 35 be collapsed when said pivoted member of said top is turned down over the said front of the cabinet, and to be moved from said collapsed position when said pivoted member of the top is raised from its turned 40 down position, and said two part members adapted, when the members thereof are in a substantially straight line and the pivoted member of said top is moved downwardly, to vary the relative position of the 45 front and back corner pieces of said cabinet.

In testimony whereof I hereunto subscribe my name at Chicago, Cook county, Illinois, this 14th day of June, 1914, in the 50 presence of the subscribing witnesses.

FRED F. BURDICK.
